UNITED STATES PATENT OFFICE.

ALBERT E. MOORHEAD, OF OAKLAND, CALIFORNIA.

PNEUMATIC DEVICE FOR COLLECTING AND REMOVING DUST.

No. 925,846.

Specification of Letters Patent.

Patented June 22, 1909.

Application filed October 19, 1907. Serial No. 398,286.

To all whom it may concern:

Be it known that I, ALBERT E. MOORHEAD, a citizen of the United States, residing at Oakland, in the county of Alameda and State of California, have invented certain new and useful Improvements in Pneumatic Devices for Collecting and Removing Dust, of which the following is a specification.

My invention relates to an improved pneumatic device for collecting and removing dust from dwellings, offices or other inhabited inclosures and from furniture and effects in such places.

The objects of my invention are to rapidly and effectually remove dust that collects in homes, offices and other places, without escape and diffusion of the dust in the inclosure as in the case of open brushes or other devices not provided with induced air currents, and in a means to loosen, concentrate and remove the dust.

This invention consists of a device or apparatus for manual use. A case open at the bottom is provided with a series of hollow tubes that are in a degree flexible and surrounding these tubes circular brushes that extend beyond the ends of the tubes to agitate and loosen the dust which, by an induced air current, is drawn into the tubes and collected in a chamber in the casing from which leads a hose or flexible tube connecting to a receiver not shown from which the air is partially exhausted by a pump or other suitable means not shown.

The device is provided with a handle preferably hollow and forming a part of the air conduit from the dust collecting device to the receiver.

Referring to the drawing herewith forming a part of this specification, and to the parts indicated by numerals, Figure 1 is a side view, partly in section, on the line $a-a$ in Fig. 2 of one of my improved dust collecting devices for manual use. Fig. 2 is a bottom view of the same device showing the disposition of the tubes and brushes on the inclosed or operating area of the implement.

1, is a casing preferably rounded at the top having a hollow extension 2 that serves as a handle for an operator and to which is attached a hose 3 that connects to a receiver and air exhausting apparatus of the usual kind.

4 indicates a plate having a number of

perforations, in each of which is inserted the top of a flexible tube 5 and a ring of bristles 7 surrounding said tube, each ring of bristles being thus spaced from the other rings. The plate 4 when inserted in the casing 1 forms a chamber 8, common to all the tubes 5, so that air is forcibly drawn through the latter into this chamber 8, and from there through the nipple or handle 2 and hose 3 as before explained. The tubes 5 are preferably made of some material that will bend or spring to accommodate uneven surfaces on which they may pass and then recover their normal position. These tubes, are, as shown, in Fig. 1, a little shorter than the cylindrical brushes 7 that surround them, so that in passing over surfaces to be cleansed the brushes 7 will come just in contact with and dislodge the dust particles so these may be drawn into the tubes 5 and expelled as explained.

The implement shown being cylindrical in form will reach into corners except a small area and pass over nearly all the surfaces requiring cleansing.

The disk or brush plate 4 is held in the casing 1 by means of screws 9 and can be interchangeable with brushes of different lengths and stiffness as the motive of the work may demand.

While in the drawings only a single form of brush is shown, it is evident the shape may be varied according to the article to be cleaned, and the purpose for which the brush is to be used, as for instance for walls, shelves, pigeon-holes, and the like.

Having thus described the motive and objects of my invention and manner of applying the same, what I claim as new and desire to secure by Letters Patent, is:—

In a dust removing implement, a casing open at the bottom, a brush plate removably secured within said casing, and having a plurality of perforations therein, and a flexible tube and a ring of bristles surrounding said tube secured at the top in each perforation, whereby said rings of bristles are spaced from each other, substantially as described.

In testimony whereof I affix my signature in presence of two witnesses.

ALBERT E. MOORHEAD.
